(57) **CLAIM**

The ornamental design for a balloon gift box as shown and described.

DESCRIPTION

FIG. 1 is front elevation view of a balloon gift box showing my new design in a closed position, and further in use with an exemplary balloon, ribbon bow and gift tag;

FIG. 2 is a front elevation view thereof, shown in an open position;

FIG. 3 is a rear elevation view thereof,

FIG. 4 is a top plan view thereof,

FIG. 5 is a bottom plan view thereof,

FIG. 6 is a right side elevation view thereof; and,

FIG. 7 is a left side elevation view thereof.

The claimed design has a uniform thickness throughout. The broken away symbols in the drawings indicate that any portions of the article beyond what is shown forms no part of the claimed design.

The broken lines are shown for the purpose of illustrating both parts of the article as well as environmental subject matter of an exemplary balloon, ribbon bow, and gift tag. None of the broken lines form part of the claimed design.
